UNITED STATES PATENT OFFICE.

ALEXANDER R. HAGNER, OF HAGERSTOWN, MARYLAND.

WINDOW-SHADE.

SPECIFICATION forming part of Letters Patent No. 731,774, dated June 23, 1903.

Application filed October 29, 1902. Serial No. 129,199. (No model.)

To all whom it may concern:

Be it known that I, ALEXANDER R. HAGNER, a citizen of the United States, residing at Hagerstown, in the county of Washington and State of Maryland, have invented certain new and useful Improvements in Window-Shades, of which the following is a specification.

This invention relates to improvements in window-shades, particularly of that class in which the shade is held at various elevations by a spring-actuated device or devices engaging with frictional contact the walls of grooves in the vertical stiles of the window-frame.

15 The object of the invention is to provide an improved window-shade of this character in which the holding devices are of simple and efficient construction and do not project so as to be in the way of a person's hand or 20 arm resting on the window-sill and which will not rattle when the invention is applied to the window of a car or other vehicle.

25 The invention consists of certain constructions and arrangements of parts hereinafter fully described and claimed, reference being had to the accompanying drawings, in which the invention is illustrated applied to a car-window; and while the invention is particularly designed for such application it is to be 30 understood that it is also applicable to other windows.

In the drawings, Figure 1 is a face view of a window with a shade embodying the features of the invention. Fig. 2 is a horizontal 35 sectional view, on a larger scale, of the shade-holding devices with the shade detached therefrom. Fig. 3 is a similar view illustrating a slightly-different form in which the invention may be embodied. Fig. 4 is a detail 40 perspective view of the end of one of the holder-rods.

The stiles *a* of the window-frame are provided in their opposing faces with vertical grooves *b*, angular in cross-section, as illustrated in Fig. 2. Within the hem *c* at the bottom of the flexible and spring-roller shade *A* or secured in any other suitable manner to said shade is a tube or casing *d*, whose ends are preferably reduced and are entered 50 into the grooves *b* with sufficient accuracy to

prevent the said tube from rattling when the window-frame is jarred and yet sufficiently loose to slide up and down in the grooves, which latter thereby serve as guides. The said tube *d* contains, as illustrated in Fig. 2, 55 two rods *f*, pivoted intermediate of their ends on studs or pins *g*, with their adjacent ends overlapping and pressed apart by an interposed transversely-acting expansion-spring *h*, which may be contracted to press the said 60 ends of the rods together by means of two buttons *i*, each of which is secured to one end of each rod and works through an aperture in the wall of the tube, so that it may be pressed upon by a person's fingers. The other 65 end of each rod *f* projects out through the end of the tube *d* and extends in a lateral direction into the correspondingly-turned portion of the contiguous angular groove, and a boxing *j* is secured or formed integral with the 70 said laterally-extending end of each rod and carries rollers *k*, adapted to roll in a slight depression *l* in the far wall of the groove; said rollers normally pressing with sufficient frictional contact against said wall, when the 75 spring *h* is allowed to act, that they will hold the shade at any desired elevation against the action of the shade's elevating spring-roller. To release the rollers in order to raise or lower the shade from one point to another, it is only 80 necessary to grasp the two buttons *i* between the forefinger and thumb and press the buttons together, which action will rock the rods *f* in a horizontal direction and will carry the rollers out of contact with the wall of the 85 groove.

In that form of the invention illustrated in Fig. 3 the angular grooves *b'* are T-shaped in cross-section and there are four rods *f*, two for each groove, as shown. In principle and 90 mode of operation this form of the invention is the same as that illustrated in Fig. 2.

It will be seen that I have provided a window-shade of the class before referred to which can be easily operated merely by pressing the two buttons *i* together, said buttons not only being susceptible of ornamentation and producing a pleasing appearance, but being also to all intents and purposes substantially flush with the face of the shade and 100

having no projecting sharp ends liable to injure a person's hands or clothes.

Having thus fully described my invention, what I claim as new, and desire to secure by 5 Letters Patent, is—

1. The combination with a window-frame whose stiles are provided with vertical grooves, and a shade in said window-frame, of a tube or casing secured to the shade; rods 10 pivoted intermediate of their ends in said tube and adapted to engage with one end, a wall of said grooves; and a spring acting to press the other ends of said rods apart whereby to rock said rods, as set forth.
- 15 2. The combination with a window-frame whose stiles are provided with vertical grooves, and a shade in said window-frame, of a tube or casing secured to said shade; oppositely-extending rods pivoted intermediate 20 of their ends in said tube and carrying at their outer ends rollers adapted for engagement with a wall of said grooves; a transversely-acting spring interposed between the inner ends of said rods whereby to press said 25 ends apart; and buttons with which a person's fingers may engage to press the said in-

ner ends of the rods together, as and for the purpose set forth.

3. The combination with a window-frame whose stiles are provided in their opposing 30 faces with vertical grooves angular in cross-section, and a shade in said window-frame, of a tube or casing secured to the bottom of the shade with its ends mounted to slide in the said grooves; oppositely-extending rods 35 pivoted intermediate of their ends in said tube with their outer ends extending into the grooves and turned in a lateral direction, and with their inner ends overlapping; rollers carried on the outer ends of said rods; an expansion-spring interposed between said overlapped inner ends; and buttons secured to 40 said inner ends and working through the wall of the tube in position to be grasped by a person's fingers, as and for the purpose set 45 forth.

In testimony whereof I affix my signature in the presence of two witnesses.

ALEXANDER R. HAGNER.
